[57] CLAIM

The ornamental design for a crash cart for hospitals, as
shown.

DESCRIPTION

FIG. 1 is a front, elevational view of a crash cart for
hospitals; showing swivel tray for defibrillator, and side
bins for tape and other equipment;

FIG. 2 is a left side view thereof, showing the relatively
narrow depth of the invention as opposed to its width
(illustrated in FIG. 1);

FIG. 3 is a right side view thereof;

FIG. 4 is a top view thereof;

FIG. 5 is a rear view thereof; and,

FIG. 6 is a bottom view thereof;

FIG. 6

FIG. 5

FIG. 4
